[57] CLAIM

The ornamental design for a keyless door lock, as shown and described.

DESCRIPTION

FIG. 1 is a top, front, and right side perspective view of a

keyless door lock showing our new design;

FIG. 2 is a vertical cross-sectional view thereof, taken along line 14—14 of FIG. 13;

FIG. 3 is right side elevational view of the base plate portion thereof;

FIG. 4 is a left side elevational view of the base plate portion thereof;

FIG. 5 is a front elevational view of the base plate portion thereof;

FIG. 6 is a rear elevational view of the base plate portion thereof;

FIG. 7 is a top plan view of the base plate portion thereof, the bottom being identical in appearance;

FIG. 8 is a front elevational view of the stop plate portion thereof;

FIG. 9 is a top plan view of the stop plate portion thereof;

FIG. 10 is a bottom plan view of the stop plate portion thereof;

FIG. 11 is a left side elevational view of the stop plate portion thereof;

FIG. 12 is a right side elevational view of the stop plate portion thereof;

FIG. 13 is a rear elevational view of the stop plate portion thereof;

FIG. 14 is a vertical cross-sectional view of the stop plate portion thereof, taken along line 14—14 of FIG. 13; and, FIG. 15 is a front elevational view of an alternate embodiment thereof, showing the stop plate portion, with the only difference from the first embodiment residing in the appearance of the central keyway aperture.
